UNITED STATES PATENT OFFICE

2,054,338

FLASK FILLING APPARATUS

Walter F. Piper, Oak Park, Ill., assignor to The
Beardsley & Piper Company, Chicago, Ill., a
corporation of Illinois

Application November 7, 1935, Serial No. 48,639

2 Claims. (Cl. 22—36)

The present invention relates generally to apparatus for filling flasks with moulding sand. More particularly the invention relates to that type of apparatus which is designed for use in a foundry or like establishment and comprises as the main or essential parts thereof (1) a substantially cylindrical casing having a downwardly extending peripheral outlet and also having in one of the end walls thereof an inlet for sand; 10 and (2) a rotary motor driven blade which is disposed in the casing and operates during rotation thereof to form the sand in the casing into wads and to sling or project the wads downwards through the outlet into a flask beneath the casing. 15 In an apparatus of this type it has been found that during rotation of the wad forming blade a large quantity of air is drawn or sucked into the casing through the sand inlet and that such air has a tendency to make the apparatus extremely noisy and also to aerate the sand in the casing to such an extent that it will not pack and form wads of the proper or desired density. 20

The primary object of the invention is to provide a flask filling apparatus of the type under consideration which is an improvement upon previously designed apparatus of the same general character by reason of the fact that it includes means for restricting or precluding the sucking or drawing of air into the casing during 30 rotation of the blade and thus operates with a minimum amount of noise and to form sand wads of the desired density.

Another object of the invention is to provide a flask filling apparatus of the type and character last mentioned in which the casing has a hopper associated therewith for directing sand through the inlet into the casing and the means for restricting or precluding entry of air into the casing during rotation of the blade consists of a 35 gate valve which is disposed in the hopper and is arranged so that it opens automatically during feed of the sand through the hopper to the casing.

A further object of the invention is to provide an apparatus of the type and character under consideration in which the gate valve for restricting or precluding the flow of air into the casing during rotation or drive of the blade is adjustably counterbalanced so that it may be set or adjusted 40 to open in response to any desired pressure of the sand.

A still further object of the invention is to provide a flask filling apparatus which is generally of new and improved construction and is not only extremely efficient in operation but is also an

improvement upon that which forms the subject matter of an application for United States Letters Patent filed by me October 18, 1934, Serial No. 748,795.

Other objects of the invention and the various 5 advantages and characteristics of the present flask filling apparatus will be apparent from a consideration of the following detailed description.

The invention consists in the several novel features which are hereinafter set forth and are more particularly defined by claims at the conclusion hereof.

In the drawing which accompanies and forms a part of this specification or disclosure and in 15 which like numerals of reference denote corresponding parts throughout the several views:

Figure 1 is a side elevation of an apparatus embodying the invention;

Figure 2 is a front view of the casing of the 20 apparatus showing in detail the construction and arrangement of the hopper for feeding the sand into the casing and also the construction and location of the adjustable counterbalancing means for the gate valve; and 25

Figure 3 is a vertical longitudinal sectional view on the line 3—3 of Figure 2.

The apparatus which forms the subject matter of the invention is designed for use in a foundry or like establishment. It operates, as hereinafter 30 described, to fill flasks with moulding sand and consists of a casing 4, a hopper 5 for delivering sand into the casing, and a rotary blade 6.

The casing 4 is substantially cylindrical and consists of an annular side wall 7 and a pair of circular or disk-like end walls 8 and 9. The annular side wall 7 is positioned normally so that its axis extends horizontally. It is preferably in the form of a casting and has a downwardly extending tangentially arranged discharge member 10. The latter constitutes an outlet for the casing and is connected by bolts 11 to the upper end of a vertically extending wad directing tube 12. The end wall 8 is formed integrally with and serves as a closure for one end of the annular side 45 wall 7 of the casing. The end wall 9 is formed separately from the side wall 7 and is removably secured to the other end of the latter by means of a pair of diametrically opposite clamping bolts 13 so that upon removal from the side wall 7 access may be had to the interior of the casing. 50 As shown in Figure 3, the end wall 9 supports the hopper 5 and has in the central portion thereof a sand inlet 14. The hopper 5 is formed of sheet metal or any other suitable material and 55

consists of a pair of triangularly shaped sides 15 and a substantially semicircular inclined bottom 16. It is adapted to receive sand from an overhead sand conveyor 17 and serves to deliver or supply the sand through the inlet 14 into the casing 4. The lower end of the bottom 16 of the hopper extends into the central portion of the casing and rests upon an out-turned lip 18 on the central portion of the removable end wall 9 of the casing. The sides 15 of the hopper extend vertically and are suitably secured to the outer face of said end wall 9. The overhead sand conveyor 17 is in the form of a horizontally extending drum supported endless belt which forms the bottom of, and receives sand from, a reservoir 19. The latter is supported at the upper end of a vertically extending frame 20 and is positioned above, and has an end opening 21 adjacent to, the casing 4. The belt is adapted to be driven and operates during drive to carry sand from the reservoir 19 and to discharge it into the hopper 5 for delivery via the inlet 14 to the casing 4.

The blade 6 is disposed in the casing 4 and is adapted to rotate or swing around the inner periphery of the annular side wall 7 of the casing. It is connected to a head 22 and a hub 23 for rotation by an electric motor 24 and operates during drive or rotation to form the sand within the casing into wads and to sling or project these wads downwards through the outlet member 10 and the tube 12 into a flask beneath the casing 4. Preferably the blade is rotated between 1200 and 1800 revolutions per minute. The sand which enters the casing by way of the hopper 5 and the inlet 14 falls into the lower portion of the casing. During operation of the electric motor 24 the blade 6 picks up the sand in the lower portion of the casing and swings it around an arcuate liner 25 until the outlet member 10 is reached. During travel around the liner the sand as the result of the action of centrifugal force and the shape of the blade is formed or packed into a dense wad of closely packed sand which when the blade reaches the member 10 is projected through the latter and thence down the tube to the subjacent flask. The liner 25 fits against the inner periphery of the side wall 7 of the casing and extends from the low side of the discharge member 10 around the side wall 7 to the high side of the discharge member. The electric motor 24 for rotating or driving the plate is positioned adjacent to the end wall 8 of the casing 4 and is secured in place by means of bolts 26 which extend through said end wall 8 and the housing of the motor. As shown in Figure 3 one end of the armature shaft of the motor projects into the casing through a hole 27 in the central portion of the end wall 8. The hub 23 is mounted on the projecting end of the armature shaft and is drivably connected to the latter by means of a key 28. The head 22 surrounds the hub. It is connected to the latter by means of bolts 29 and supports the blade 6. The motor casing and hopper are supported from above by means of a universal joint 30. This joint, as shown in the drawing, extends between the housing of the electric motor 24 and the distal end of an arm 31 which projects horizontally from, and is secured to the upper end of the frame 20. The joint 30 permits of limited universal movement and enables the operator of the apparatus to swing the tube 12 into different positions for wad discharging purposes.

In order to restrict or preclude air from entering the casing 4 with the sand a gate valve 32 is

provided. This valve is associated with the hopper 5 and consists of a sheet metal plate 33 and a horizontally extending pivot shaft 34. The shaft, as shown in Figure 3, extends between the upper and inner corner portions of the sides 15 of the hopper and is journaled at its ends in a pair of bearings 35. The latter abuts against the outer face of the removable end wall 9 of the casing 4 and are welded or otherwise fixedly secured to the inner faces of the hopper sides 15. The plate 33 extends downwardly and outwardly from the shaft 34 and is fixedly connected to the latter so that it is free to swing downwards from a normal position wherein it closes the hopper, into an open position wherein sand is permitted to slide or pass downwards along the hopper bottom and thence into the casing 4. The side edges of the plate are parallel to one another and engage slidably the inner face of the hopper sides 15. The bottom edge of the plate is rounded and is adapted when the plate is in its closed position to engage the inner face of the bottom 16 of the hopper. The plate is slightly longer than the shortest distance between the pivot shaft 34 and the hopper bottom 16 and as a result the plate cannot swing upwards past its closed position that is upwards beyond the position shown in dotted lines in Figure 3. In order normally to return the plate 33 in its closed position, a counterweight is provided. This weight is slidably mounted on an arm 37 which is connected to one end of the pivot shaft 34 and extends at right angles to the latter. Preferably the arm is arranged so that it extends horizontally when the plate 33 is in its closed position. A set screw 38 extends through the counterweight and serves releasably to hold the counterweight in place on the arm 37. When the set screw is released the counterweight may be shifted longitudinally of the arm in order to vary its effective weight. When the apparatus is in operation sand is delivered by the overhead conveyor 17 into the hopper 5. It travels down the hopper, strikes against and opens the plate 33 of the gate valve and then enters the casing 4 where it is formed into wads by the blades 6 as hereinbefore described. The counterweight is preferably arranged on the arm 37 so that the gate swings into its open position only when struck by the sand. When the gate is struck by the sand it will open only enough to permit the sand to slide downwards into the casing and thus restricts or precludes the sucking or drawing of air into the casing during rotation of the blade 6. By restricting or precluding the flow of air into the casing with the sand, the apparatus runs in an extremely quiet manner and the sand within the casing is not aerated to such an extent that it will not pack or form wads of the proper or desired density. The counterweight 34 is preferably positioned on the arm 37 so that its movement or effective weight is such that the suction within the casing during rotation of the blade 6 is not sufficient to open the plate 33 but the force of the sand striking against the plate is sufficient. In the event that it is desired to increase or decrease the amount of force that is necessary to swing the plate 32 into its open position the counterweight is adjusted in one direction or the other on the arm 37.

The herein described flask filling apparatus is extremely efficient in operation in that it includes the gate valve 32. Since the valve itself is of simple construction and design the cost of the 75

apparatus with the valve is not materially greater than it is without the valve.

The invention is not to be understood as restricted to the details set forth, since these may be modified within the scope of the appended claims without departing from the spirit and scope of the invention.

Having thus described the invention, what I claim as new and desire to secure by Letters Patent is:

1. In an apparatus for filling flasks with molding sand, the combination of a casing having an inlet and an outlet, a hopper communicating with the casing inlet, means for delivering a stream of molding sand into the hopper for delivery to the casing via the inlet, a rotary motor driven blade disposed in the casing and operative during rotation thereof to form the sand in the casing into wads and project the wads through the casing outlet, and a pivoted gate valve disposed in and extending across the hopper and arranged and adapted to be engaged and swung by the top portion of the stream regardless of variations in

the depth of the latter and serving automatically to prevent air from being sucked into the inlet by the blade during operation of the apparatus and delivery of the stream of sand.

2. In an apparatus for filling flasks with molding sand, the combination of a casing having an inlet and an outlet, a hopper communicating with the casing inlet, means for delivering a stream of molding sand into the hopper for delivery to the casing via the inlet, a rotary motor driven blade disposed in the casing and operative during rotation thereof to form the sand in the casing into wads and project the wads through the casing outlet, and an inwardly swinging self-closing gate valve disposed in and extending across the hopper and arranged and adapted to be engaged and swung inwardly by the top portion of the stream regardless of variations in the depth of the latter and serving automatically to prevent air from being sucked into the inlet by the blade during operation of the apparatus and delivery of the stream of sand.

WALTER F. PIPER.
